UNITED STATES PATENT OFFICE.

ANDREW A. McCREE, OF ST. PAUL, MINNESOTA.

VALVE-ACTUATING MECHANISM FOR CONCRETE MIXERS.

Application filed April 30, 1926. Serial No. 105,847.

The present invention appertains to novel means for automatically operating the water control valve used in conjunction with concrete mixers, and is particularly adapted to 5 that type of balanced valve disclosed in my co-dependent application Serial Number 55,748, filed September 11th, 1925.

As set forth in my prior application just mentioned, the mixer apparatus embodies a 10 double water tank arrangement by means of which a measured quantity of water for a mix is always in readiness for the next batch of aggregates, one tank refilling with water while the other is discharging its contents, 15 such action being under the control of a reciprocatable valve member, movements in opposite directions of which establish communication between the respective tanks and the mixer. I desire it to be understood, however, 20 that I do not limit its utility to the particular type of valve referred to.

Primarily, however, the problem has been to devise an operating mechanism which is 25 capable of shifting the valve mechanism in corelation to and under the control of movement of the skip in effecting its discharge of the aggregates into the mixer. To be more specific, the shifting of the valve when controlled from the skip as most to be desired, 30 must take place only on the discharging or elevating movement of the skip and not on its lowering movement. Further than this, the operative connections made for this purpose must permit certain degrees of movements of the skip without entailing any shift 35 of the valve, in order that requisite normal operations of the apparatus may not be interfered with.

Broadly speaking, my invention comprehends a novel mechanical movement wherein 40 a single reciprocation of the operated means is produced by two reciprocations of the operating means, acting in one direction only. My invention, therefore, has 45 for its primary object the provision of a valve actuator so constructed and arranged as to impart one to-and-fro movement to the valve to two such movements of the skip.

A further objective is to provide actuating 50 mechanism embodying a link motion, so-called, operable by the hoisting means for the skip to shift the water valve, the construction of said link motion being such that the skip may be given increments of movement 55 from its lowered as well as from its

elevated or charging position without effecting any movement of said valve.

Other novel characteristics reside in the provision of adjusting means for regulating the time of opening of the valve and for regulating also the throw of the valve actuator. 60

Other objects and advantages of the invention will be hereinafter set forth and the novel features thereof defined by the appended claims. 65

In the accompanying drawings:

Figure 1 is a side elevation of a concrete mixer with my valve actuating mechanism applied thereto;

Figure 2 is a fragmentary plan view showing the arrangement of the water control valve with reference to the plural water tanks; 70

Figure 3 is a side elevation of the actuating mechanism forming the special subject matter of the present invention; 75

Figure 4 is an end elevation thereof; and

Figure 5 is a detailed view of the valve mechanism with which the invention co-80 operates.

Like reference characters designate corresponding parts throughout the several figures of the drawing.

Referring to the drawings, A represents a well known type of concrete mixer including 85 the mixer drum B, the skip C, and its hoisting cable D. The hoisting cable passes over the sheave E mounted at the top of the frame F and around the winding drum G. Mounted above the mixer drum is a pair of water tanks H, the outflow pipes I of which communicate with a valve casing J. From the opposite ends of this casing the water is delivered to the mixer by the pipe K under the control of the double piston valve L to which 90 is connected the valve rod M extending from one end of the valve casing. This apparatus is well known and fully set forth in my prior application hereinbefore referred to, and for these reasons need not be more specifically 95 described herein. It suffices to say that the mechanism which forms the subject matter of the present invention is operably connected to the valve rod M to impart back and forth movement to the valves whereby the 100 contents of the water tanks may be alternately delivered to the mixer.

On the upright of the frame F, and approximately on a level with the valve casing J, I pivotally secure a double bell crank lever 110

1, the longer lever arm of which is longitudinally slotted from end to end, as indicated at 2. At each end the slot is formed with a dwell or offset 3, the function of which 5 will be more clearly stated hereinafter. The short lever arm of the bell crank 1 is connected by means of the rod 4 with a second bell crank 5 (Figure 2) which in turn is connected to the valve rod I by the link 6. 10 Obviously movement of the bell crank 1 from its full line position of Figure 3 to the dotted line position will shift the valve rod in one direction and its movement in the opposite direction will return the valves to the 15 original position.

Mounted upon a guide rod or support 7 attached to the frame F is a cross head or slide 8, said slide having a stud 9 projecting therefrom. To this stud, one end of an 20 actuating rod 10 is connected, said rod having a roller at its other end projecting into the slot 2 of the bell crank 1 and in the operation of the device as hereinafter explained the roller finds a seat in a dwell 3. 25 The stud 9 also has mounted thereupon one end of a connector rod 12, the other end of which is adjustably connected to a stirrup 13, in turn mounted upon the axle 14 of a sheave 15. The sheave is mounted between 30 the sides of the strap arm 16 which is swingingly mounted on the axle E' of the sheave E. In order to adjust the arc of this strap arm 16 a series of openings 17 is provided, this adjustment being one of the main features 35 of my mechanism. It will be apparent from a consideration of Figure 3 that the sheave 15 coacts with the hoisting cable D for the skip which in the hoisting movement of the skip functions to raise the slide 8 hereinbefore mentioned. As the slide moves 40 upwardly the roller 11 on the end of the rod 10 engages in the seat 3 in the lower end of the slot 2 and continued upward movement of the slide rocks the bell crank lever about 45 its pivot as shown in dotted lines in Figure 3. Such movement in turn actuates the rod 4, the bell crank 5 and finally the valve rod I. This movement of the valves is timed to take place at the proper moment coinciding 50 with the charging of the mixer by the skip.

As soon as the contents of the skip have been charged into the mixer the skip is allowed to descend to its loading position, which in turn permits the slide 8 to drop 55 downwardly to its lowermost position, the end of the rod 10 sliding along the slot 2 until the roller 11 reaches the opposite end of said slot. Under such a condition it will be apparent that the water control valves 60 were not actuated, which is the desirable condition because the water from one of the tanks H is flowing into the mixer while the other of the tanks H is being refilled through the water supply N. However, on the next 65 elevation of the skip the roller 11 is again

engaged in the dwell at the lower end of the slot 2 and the bell crank 1 is shifted in the opposite direction to that first described. Such movement drives the valve rod in the opposite direction, effecting a shifting of the valves and the flow of the water into the mixer with the charging of the aggregates from the skip. The lowering movement of the skip takes place again as before described, without an actuation of the valve mechanism, so that as hereinbefore premised it will be apparent that two hoisting movements of the skip are required to make one complete reciprocation of the valve rod, owing to the one-way action of the mechanism connected thereto.

The timing of the valves so that the outflow of the water from the tanks takes place at the proper time, may be adjusted by the adjustment of the strap arm 16, as before mentioned. By screwing the connector rod 12 in or out of the stirrup 13 I am able to regulate the throw of the bell crank 1. This adjustment obviously raises or lowers the sheave 15 and controls the point of commencement of the discharge of the water from the supply tanks.

Owing to the play or freedom of movement of the actuating rod 10 in the slot 2 of the bell crank it will be apparent that the skip may be raised from its contact with the surface a short distance as when it is desired to move the mixer apparatus, without effecting any actuation of the valve mechanism, and in like manner when the skip is in its charging position this arrangement of the parts permits the customary oscillation of the skip to jar loose the materials from the skip in the charging of the mixer with the contents.

Having thus described my invention, what I claim as new and desire to secure by Letters Patent is:—

1. In concrete mixing apparatus, the combination with a valve device and mixer charging means, of an operating connection between said device and charging means and arranged to be actuated upon successive charging movements only of said means.

2. In concrete mixing apparatus, the combination with a valve device and mixer charging means, of an actuator connected to said valve device, and means intermediate the charging means and the actuator operable to shift the latter in opposite directions upon successive charging movements of the charging means.

3. In concrete mixing apparatus, the combination with a valve device and mixer charging means, of an oscillatory actuator connected to said valve device, and means for automatically oscillating said actuator in opposite directions as an incident to movements of the charging means in only one direction.

4. In concrete mixing apparatus, the combination with a valve device and mixer charging means, of an oscillatory actuator connected to said valve device, and reciprocating means operable in one direction to shift the actuator and in the opposite direction without shifting the same whereby two complete reciprocations of the reciprocating means produce one complete oscillation 10 of the actuator.
5. In concrete mixing apparatus, the combination of a control valve, a loading skip, means for shifting the skip from loading to charging position, and actuating mechanism 15 for said control valve operable only from said shifting means.
6. In concrete mixing apparatus, the combination of a mixer control member, an oscillatory member connected thereto, and a reciprocable member having sliding connection 20 with said oscillatory member for actuating and non-actuating movements thereof.
7. In concrete mixing apparatus, the combination of a mixer control member, a bell crank connected thereto, and a slidable actuator connected to said bell crank in such manner as to shift the control member in opposite directions by a shift of the actuator from one side of the axis of the bell 30 crank to its other side.
8. In concrete mixing apparatus, the combination of a water control valve, a double bell crank connected thereto, and a skip operated actuator having slidable connection 35 with the bell crank to shift the latter in opposite directions.
9. In concrete mixing apparatus, the combination of a water control valve, a double bell crank connected thereto, skip hoisting means, and a rod operable by said means and having a connection with said bell 40 crank.
10. In concrete mixing apparatus, the combination of a water control valve, a double bell crank connected thereto, skip hoisting means, and means swingingly supported in the path of the hoisting means and connected to said bell crank for shifting 45 the latter in opposite directions.
11. In concrete mixing apparatus, the combination of a water control valve, actuating mechanism therefor including a bell crank having opposing lever arms, a slide member shiftably connected thereto and an 50 actuating rod connected at one end to the slide member, and a skip hoisting cable cooperative with the other end of the actuating rod.
12. In concrete mixing apparatus, the combination of a water control valve actuating mechanism therefor including a bell crank having opposing lever arms, a slide member shiftably connected thereto and an actuating rod connected at one end to the 55 slide member, a skip hoisting cable cooperative with the other end of the actuating rod, a loading skip, and means for controlling the movement of the rod in relation to movement of the skip. 70
13. Valve actuating mechanism for concrete mixers, comprising an oscillatory member, a reciprocating member and a connector rod between said members having its connection with the oscillatory member shiftable from one side of its pivot to the other whereby to impart an oscillatory movement to one of said members to two reciprocatory movements of the other. 75
14. In a concrete mixing apparatus, the combination with a valve device and mixer charging means, of an operating cable for said means adapted to actuate the device in the charging movement of said means. 80
15. In a concrete mixing apparatus, the combination with a valve device and a charging skip, of a cable for elevating the skip, and means actuated in the cable movement for operating the valve device. 85
16. In concrete mixing apparatus, the combination of a pair of water tanks, a water control valve common thereto, an oscillatory member connected thereto, and means for actuating said oscillatory member to impart movement to and fro to the 90 control member upon successive actuating movements of said means.
17. In concrete mixing apparatus, the combination of a pair of water tanks, a valve common thereto movable in one direction to discharge one tank and in the other direction to discharge the second tank, an oscillatory member connected to the valve, and mixer charging means shiftably connected to said oscillatory member to impart movements in opposite directions there-to upon successive charging movements. 100 105

In testimony whereof I affix my signature.

ANDREW A. McCREE.
